UNITED STATES PATENT OFFICE.

LEWIS J. CHERRY, OF HOUSTON, TEXAS.

COMBINATION TOOL.

Application filed July 5, 1922. Serial No. 573,025.

This invention relates to new and useful improvements in a combination tool.

One object of the invention is to provide a tool of the character described specially designed for use by carpenters and embodying a protractor, and spirit and plumb levels, all conveniently and compactly combined.

Another object of the invention is to provide a device of the character described which is of simple construction, may be cheaply and easily manufactured and readily applied to the work.

With the above and other objects in view the invention has particular relation to certain novel features of construction, use and arrangement of parts, an example of which is given in this specification and illustrated in the accompanying drawings, wherein:—

20 Figure 1 shows a side view of the device, as used for a protractor.

Figure 2 shows a sectional view thereof.

Figure 3 shows a side view of the protractor head, showing the spirit and plumb 25 levels, and

Figure 4 shows a plan view of the plumb level.

In the drawings the numeral 1 designates the protractor head. At one end this head has a cut away portion 2, in which the spirit level 3 is mounted. The respective ends of this spirit level have the bearings 4, 4, through which the outwardly threaded rods 5 pass, and threaded onto said rods above 35 and below said bearings are the adjusting nuts 6, 6, by means of which the level may be adjusted. The ends of the rods 5 are suitably anchored to the head. The other end of the head has a circular opening 7 in

40 which the protractor disc 8 is rotatably mounted. This disc is suitably graduated so as to indicate different angles as it is turned relative to the gauge mark 9 on the head. The upper side of the head has a

45 long narrow groove 10, and the end of the head adjacent the disc 8 has a similar vertical groove 11. Fitted through the groove 10 there is the blade 12 which is gauged to 50 designate linear measurements, and one side of this blade has a lengthwise groove 13.

The disc 8 has a central cut away portion

14 in which is located a thumb nut 15 which is threaded onto the inner end of the clamp rod 16. This rod works through a radial bearing 17 of the disc 8 and its outer end 55 is formed with a lateral catch 18 which is received by the groove 13. By loosening the nut 15 the blade may be adjusted to any desired position and there held by tightening up the nut 15, the adjacent side of the disc 8 60 being also grooved to receive said blade.

The numeral 19 designates a level base, the upper side of which has a dovetailed rib 20, and the lower edge of the head 1 has a correspondingly shaped groove 21 to 65 receive said rib, thus forming means for the attachment of the head 1 to said base, when the device is to be used for a spirit level. When the device is to be used as a protractor the base 19 is removed and the edge 22 is 70 placed against the edge of the board to be cut, and the blade 12 then adjusted to the desired angle, said blade may be secured at said angle by means of the set screw 23, and the pencil line then drawn along the gauged 75 edge of the blade, forming a mark along which the board may be cut.

Referring again to Figures 3 and 4, a plumb level 37 is shown, to one side of which there is secured, a blade adapted to fit into 80 the end groove 11. This blade has a vertical groove 39 into which the catch 18 may be engaged to hold the plumb level secured to the head 1. The edge 22 of the head 1 is then placed in vertical position against the 85 wall or other structure and the plumb level will indicate whether or not said structure is plumb.

What I claim is:—

A combination tool including a level base, 90 a protractor head, said head and base being provided, one with a rib and the other with a groove adapted to receive said rib, said head having a cut away portion at one end, a detachable spirit level mounted in said cut 95 away portion, means for adjusting the respective ends of said spirit level, the other end of said head having a circular opening, a graduated disc rotatably mounted in said opening, one side of said head having a long 100 narrow groove and the end of said head adjacent the disc having a transverse groove,

a graduated blade seated in said first mentioned groove, said blade having a length-wise groove in one side, said disc having a central cut away portion and a radial bearing, a thumb nut located in the cut-away portion of said disc, a clamp rod working through said radial bearing in said disc into

one end of which said thumb nut is threaded and whose outer end has a catch which is received by the groove of said blade. 10

In testimony whereof I have signed my name to this specification.

LEWIS J. CHERRY.
